UNITED STATES PATENT OFFICE.

EDMUND HAWTHORNE MICKLEWOOD, OF PLYMOUTH, ENGLAND.

ROTARY VALVE FOR INTERNAL-COMBUSTION ENGINES AND OTHER HEAT ENGINES.

Application filed August 18, 1924. Serial No. 732,845.

To all whom it may concern:

Be it known that I, EDMUND HAWTHORNE MICKLEWOOD, a subject of the King of Great Britain, residing in Plymouth, England, have invented certain new and useful Improvements in Rotary Valves for Internal-Combustion Engines and Other Heat Engines, of which the following is a specification.

10 This invention relates to rotary valves controlling the admission and discharge of the working fluid in internal combustion and other heat engines, and particularly in two-stroke internal combustion engines of the type described in United States Patent No. 856,790 in which the engine piston is stepped and the enlarged outer end, working in an annular chamber, serves to induce a charge of working fluid and compress it 20 into the cylinder and also to scavenge the latter.

The object of the invention is to provide a valve for such engines which will be freely rotatable, unsubjected to any varying pressure whatever, and to attain this all end thrust on the valve is eliminated and particularly that due to the pressure developed in compressing the charge of working fluid into the engine cylinder.

30 Further, to eliminate cross strains upon the valve, such as are inseparable from any usual arrangement of direct drive, e. g., a chain drive, of the rotary valve spindle, the spindle is so coupled with the chain wheel 35 or the like from which it is driven that the circular or rotary movement of the wheel is imparted to the spindle, while all cross strain or pressure is eliminated.

With these objects the rotary valve controlling the admission of the working fluid and of the scavenging air to the engine cylinder comprises a hollow cylinder mounted to rotate or oscillate upon a sleeve which is rigid with or secured direct or indirectly to the engine cylinder and has a transverse diaphragm arranged to take the back thrust due to the establishment of pressures in the working of the engine, e. g., the compression of the charge of working fluid, to which pressures the valve itself would otherwise be subjected, this diaphragm dividing the sleeve into two compartments and separating the ports provided in the sleeve and valve and valve casing for the control of the working fluid charge from those which control the scavenge charge.

enging charge. The valve casing is preferably constituted by a sleeve coaxial with the sleeve upon which the hollow cylindrical valve rotates or oscillates, the valve having 60 a fluid-tight surface contact with the inner and outer sleeves.

The outer cylindrical valve casing and the inner sleeve may be integral with each other or separately formed, and either or 65 both may be integral with the engine cylinder casting or suitably secured thereto.

To eliminate cross strains on the valve spindle, a disc or arm on the end of the valve spindle may be coupled with the 70 chain wheel by means of pin and slot connections, the chain wheel being in this case conveniently mounted to rotate upon a boss forming an axial extension of the rotary 75 valve cover, while the spindle of the rotary valve passes through an axial bore in this boss and is provided at its outer end with the disc or arm from which coupling pins extend laterally to engage the chain wheel, or vice versa.

One embodiment of the invention is illustrated in the accompanying drawings, wherein Fig. 1 is a vertical cross section of part of an engine cylinder taken through the centre of the rotary valve controlling 80 the working fluid and scavenging air supply; Fig. 2 is a side elevation of the valve in the position in which it is shown in Fig. 1; Fig. 3 is a section on the line 3-3 of Fig. 1; Fig. 4 is a section on the line 4-4 90 of Fig. 1; and Fig. 5 is a central vertical section, on a smaller scale than Fig. 1, of one cylinder of an engine embodying the invention.

In the drawings A represents the working cylinder and B the working piston, while A' is an annular chamber in which works an annular pump plunger B' forming a part of a stepped trunk piston, this arrangement of working cylinder and piston and pump cylinder and piston being as described in the aforesaid United States patent specification.

The rotary valve which deals with cool gases only, namely the working fluid and 105 the scavenging air, is mounted in a valve box or casing which comprises two concentric cylinders or sleeves C, D which may be integral with each other. One end of this valve box is fitted to the wall of the working cylinder and pump which is suitably recessed for the purpose and is rigidly con-

nected therewith as by means of bolts or studs through a flange C^0 on the outer sleeve, the end of which may be tapered as shown, so that it can be drawn tightly into a 5 tapered recess in the cylinder wall. Alternatively, the valve box may be secured to the engine cylinder wall through the medium of the inner sleeve D. The latter is constructed or provided with a transverse 10 diaphragm E which takes the back thrust due to the establishment of pressure in the working of the engine, which otherwise would be transmitted to the valve itself. The diaphragm E thus divides the chamber 15 within the inner sleeve D into two compartments F, G and a port F' connects compartment F with the annular space between the inner and outer sleeve which is filled by the rotary cylindrical valve. The compartment 20 G has diametrically opposite ports G', G² communicating with the same annular space, and this compartment also communicates with the upper end of the pump cylinder A' through a port G³. The outer sleeve C 25 has two diametrically opposite ports C', C² adjacent to the working cylinder and connecting the annular space between the two sleeves respectively with a passage or port H leading to the working cylinder and with 30 the working fluid induction chamber K. The outer sleeve C has a third port C³ near its outer end which is connected, as by pipe P, with a port P' opening into the lower end of the annular pump or compressor chamber 35 A'. Further, both sleeves are pierced with two diametrically opposite ports I, the aligning ports I on one side of said sleeves admitting air to the chamber F, while the aligning diametrically opposite ports I of 40 said sleeves communicate with a pipe or passage, not shown in the drawings, which may lead to a second working cylinder, in the case of a multi-cylinder engine, or to a scavenging air reservoir in the case of a 45 single cylinder engine.

The valve itself is constituted by a hollow cylinder J which fills the annular space between the two sleeves of the valve box. This cylinder has three ports, namely a port J' 50 which, in the rotation of the valve, registers successively with the diametrically opposite ports I in the internal and external sleeves of the valve box; a second port J² which registers successively with the ports G', C' 55 on the one hand and the ports G², C² on the other; and a third port J³ adapted to register with the port F' in the internal sleeve of the valve box and, when so registering, to establish communication between the 60 compartment F and the passage H through port C'.

The valve J is rotated by means of a spindle L which is journalled in the boss of a cover M closing the outer end of the valve 65 box and is suitably secured to the valve it-

self as by being keyed to an internal-boss J⁰ integral with or secured to the cylindrical valve.

The spindle L is driven from a sprocket wheel or pulley N freely mounted upon the boss M' of the cover plate M through pin and slot connections between the driving wheel N and a disc O secured upon the valve spindle L, such driving connections being preferably equally spaced around the 75 driving wheel N. In Fig. 1 the disc O is shown as provided with two diametrically opposed pins O' which engage in two radially elongated holes or slots N' in the driving wheel N. By this method of driving the spindle the circular or rotary movement of the sprocket wheel N is imparted to the spindle, while all cross strain or pressure to which the driving wheel may be subject is eliminated as far as the spindle is concerned, firstly by transmission to the fixed boss on which the driving wheel rotates, and secondly by the pin and slot driving connection between the sprocket wheel and disc O. 90

The port J² controls the induction of the working fluid on the outstroke from chamber K (into which it is admitted through inlet K') through ports C², G², G³ to pump chamber A' upon the upper side 95 of pump piston B', and upon the instroke controls the transfer of the charge of working fluid from chamber A' through ports G³, G', C' and passage H to the engine cylinder. 100

The valve port J' controls the admission of scavenging air on the instroke through one set of ports I in the outer and inner sleeves of the valve casing to the chamber F, whence it passes through the open end 105 of the valve and port C³ to the compressor chamber A' below the piston B', while the valve port J³ establishes communication between the compressed scavenging air and the working cylinder at such time as the 110 exhaust valve Q (Fig. 5) is open.

The control of the admission of scavenging air to the cylinder is shown as effected by means of a port J³ so cut in the valve that while it establishes communication between ports F' and C', it also cuts off communication between ports G', and C'. 115

Having thus described the nature of the said invention and the best means I know of carrying the same into practical effect, 120 I claim:

1. In internal combustion engines and other heat engines in which charges of working fluid and of scavenging fluid are alternately forced into the engine cylinder, 125 a rotary valve controlling the admission into the cylinder of the working and scavenging charges, comprising a ported cylindrical sleeve rigid with the engine cylinder, an open-ended cylinder mounted to rotate 130

upon said sleeve, and a transverse diaphragm extending across said sleeve at an intermediate point of its length and separating the ports in said sleeve into two groups.

2. In internal combustion engines and other heat engines in which charges of working fluid and of scavenging fluid are alternately forced into the engine cylinder,

10 a rotary valve controlling the admission of the working and scavenging fluids to the engine cylinder, comprising two fixed concentric sleeves a hollow cylinder mounted to rotate within the annular space between

15 the said sleeves, ports in the said hollow cylinder and sleeves and a transverse diaphragm dividing the inner sleeve into two compartments and separating the ports which control the working fluid charge 20 from those which control the scavenging charge.

3. In internal combustion engines and other heat engines in which charges of working fluid and of scavenging fluid are 25 alternately forced into the engine cylinder, a rotary valve controlling the admission of the working and scavenging fluids to the

engine cylinder, comprising two fixed concentric sleeves, a hollow cylinder mounted to rotate in the annular space between the 30 said sleeves, two ports in the said hollow cylinder and two sets of ports in the said fixed sleeves, one set registering with one of the ports in the hollow cylinder, and the other set registering with the other port 35 therein and a transverse diaphragm extending across the inner fixed sleeve and separating the two sets of ports therein.

4. In internal combustion engines and other heat engines in which charges of 40 working fluid and of scavenging fluid are alternately forced into the engine cylinder, a rotary valve according to claim 3 provided with a third port which is adapted to establish communication between one 45 compartment of the inner sleeve and a passage leading to the engine cylinder, and also to cut off communication between a second compartment of the said inner fixed cylinder and the said passage. 50

In testimony whereof I have signed my name to this specification.

EDMUND HAWTHORNE MICKLEWOOD.
